UNITED STATES PATENT OFFICE.

J. C. HAWKINS, OF NEWTON, IOWA.

PAPER-FASTENER.

1,180,594.

Specification of Letters Patent.

Patented Mar. 2, 1915.

Application filed November 3, 1911. Serial No. 658,331.

To all whom it may concern:

Be it known that I, J. C. HAWKINS, a citizen of the United States, residing at Newton, county of Jasper, and State of Iowa, have invented a certain new and useful Paper-Fastener, of which the following is a specification.

It is the object of the present invention to provide an instrument whereby sheets of paper may be secured together by means of a tongue cut from the sheets and then folded backward through a slit in such a way that, while still integral with the sheets, it serves as a clip or fastener for holding them together.

According to the present invention the cutting and slitting knives and the tucker, which works in conjunction therewith to fold the tongues backward through the slit, are all mounted in such a way as to be particularly durable and reliable in operation, and free from many of the complex features which have heretofore characterized instruments of this general character. The tucker of the present invention is pivotally supported and is so arranged as to act positively on the tongues without being subjected to strain or fatigue when not in use.

The details of my invention will be better understood by reference to the accompanying drawings, wherein,

Figure 1 is a sectional elevation of the fastener with the jaws distended and in position to receive the paper to be fastened, Fig. 2 shows the jaws squeezed together and the tongue of paper bent through the eye of the slitting knife, Fig. 3 illustrates a modification wherein the knives are movable with a tubular section mounted to slide through a hollow standard, Fig. 4 shows the tongue of paper pushed through the slit and holding a plurality of sheets together, and Fig. 5 is a reverse view of the product shown in Fig. 4.

In the construction shown in Figs. 1 and 2, the fastener comprises a pair of operating handles 1 and 2 pivotally mounted at 3 and having projecting portions 4 and 5 which form bifurcations for actuating the parallel jaws of the fastener. The upper jaw 5 is pivotally connected to the extension 4 by means of a pin 6 and has a slot 7 slidingly engaging a transverse pin 8 rigidly mounted on the operating handle 1. A coiled spring 9 connects the pin 6 with the pin 8 and serves to hold the device normally in a dis-

tended position, as illustrated in Fig. 1. The lower jaw 10 is pivotally mounted on a pin 11 and is notched to slide on a pin 12. The helical spring 13 of the lower jaw is connected to the pin 12 through a yoke 14. The cutting mechanism of the fastener comprises a knife 15 seated against the roof of the upper jaw, this knife having a beveled lower edge shaped to cut a V-shaped tongue from sheets of paper slipped between the jaws of the fastener. At the rear of this cutting knife is a slitting knife 16 sharpened to cut a slit at the base of the paper tongue and having an eye 17 into which that tongue may be threaded automatically. The knives 15 and 16 are preferably shaped from the same piece of metal, the upper end of which is in the form of a box, tightly gripped and held in place by transverse rivets 18 and 19. A die-plate 20 is fixed upon the upper side of the lower jaw by means of a screw 21 provided with a nut 22. The front end of the die-plate is held by a screw 24 having a nut 25 serviceable as a stop for the stripper plate. The stripper plate 26 is located above the die-plate 20 and is held at its rear end by the bolt 21. The front end of the stripper plate is free to move up and down through a limited distance and has the function of holding the paper sheets with a yielding grip while the cutting and slitting knives are being withdrawn from the paper. Stamped up from the stripper plate is a lug 27 acting as a guide for the folder in a manner hereinafter set forth in detail. The folder 28 of my present invention is in the shape of a bell-crank and is pivotally mounted on a transverse shaft or pin 29. The folder is also provided with a shoulder 30 against which a coiled compression spring bears with gentle pressure.

When the device is in its inactive position, as illustrated in Fig. 1, a plurality of sheets of paper may be slipped between the stripper 26 and the die-plate 20 in position to be cut by the knives 15 and 16. By squeezing on the operating handles, the knives can be forced into the paper, cutting therefrom a tapering tongue, as illustrated in Fig. 4, and also cutting a slit into which that tongue may be tucked or folded. The folding operation is effected by means of the pivoted folder 28. Initially, the lower and longer arm of this folder rests with gentle pressure on the upstanding lug 27, but, as the jaws approach each other, this arm slips

by the end of the lug and presses downward and backward on the paper tongue, ultimately bending it through the eye 17 of the slitting knife into the position illustrated in Fig. 2. A part of this bending is effected because of the pressure of the spring 30, but the final entrance of the paper tongue into the eye is made positive by direct engagement of the short arm of the folder with the top of the lug 27.

With the tongue cut from the paper and folded back as in Fig. 2, the next operation consists in releasing the handles and allowing the slitting knife 16 to pull upward on the end of the tongue, drawing it upward through the slit into its final position, as illustrated in Fig. 5. During the first part of this movement, the folder 28 remains in contact with the tongue, preventing it from springing back of its own elasticity, and allowing the slitting knife to secure a good grip on the tongue before the backward thrust of the folder is removed. On subsequent outward movement of the jaws the folder rides upward with its lower curved arm bearing against the lug 27, while, simultaneously, the slitting knife pulls the tongue of paper through the slit and completes the fastening as shown in Figs. 4 and 5, which show bottom and top views of the completed fastening with the tongue A cut from the sheets and tucked through the slit B to serve as an attaching clip.

In the construction just described, the folder 28 is preferably made from tough steel, strong and well adapted for rough usage, being substantially rigid and inelastic. It is not subjected to fatigue when the instrument is inoperative and therefore is not subject to early crystallization and resultant breakage. All the spring parts of the structure are independent of the cutting elements and are of standard form and easily renewable.

The modification illustrated in Fig. 3 comprises a base 31 carrying a standard 32 held in place by screws 33, which are seated in slots, allowing a slight transverse adjustment of the standard. At the upper end of the standard is a vertical bearing 34 through which passes a cylinder 35 encompassed by a coiled spring 36 and provided at its top with a knob 37. This cylinder 35 is slotted to receive the smooth end of a screw 38 which serves to prevent rotation of the cylinder in its bearing, but allows free vertical movement thereof when the cylinder is pressed down by the hand of the operator or is lifted by the action of the spring 36. Within the lower end of the cylinder 35 is a cylindrical fitting 39 carrying near its front the V-shaped cutting knife 40 and carrying at its rear the slitting knife 41, the latter being held rigidly in position by set screws 42 and 43 suitably recessed in the fit-

ting. The folder is pivotally mounted on a transverse pin 44 and comprises a lower curved arm 45 and a short upper arm 46. The folder is also equipped with a coiled spring 47, whereby it may be at all times held in proper operative position. The stripper 48 is of tubular outline enveloping the lower end of the vertical cylinder 35 and mounted to freely slide with respect thereto. The helical spring 49 separates the lower ends of the stripper and the cylinder 35, while permitting relative movement thereof and serves to push the stripper downward when the cylinder is in its lowermost position. A guideway 50, shown in dotted lines at the rear of the structure, is relied on to prevent rotation of the stripper about the cylinder. The stripper 48 is provided with a lug or stop 51 inclined backward from the cutting knife and in position for engagement with the respective arms of the folder. This lug 51 is preferably struck up from the metal of the stripper, so that the stripper and all the parts movable directly therewith form parts of a single metal structure having openings at the bottom through which the knives may perform their normal functions. The operation of the structure shown in Fig. 3 is, in essential particulars, the same as that previously set forth in connection with Fig. 1. Under pressure on the knob 37, the knives are forced through the sheets of paper 52, cutting loose a tapering tongue which thereafter is folded backward by the folder 45 and tucked into the eye of the slitting knife, the stripper 48, in the meantime, holding the sheets of paper firmly against the base and its supported die 53. The final backward bending of the folder is made positive and powerful by the direct engagement of arm 46 with the top of the stop 51. On the return stroke the folder remains in engagement with the paper for a time long enough to insure a good grip in the eye of the slitting knife, and thereafter swings outward, around the shoulder of lug 51, into its initial position. In this modification, as in the modification first described, the knives are independent of the folder; and the folder need not be of resilient material and, consequently, is not subjected to crystallization and fatigue.

What I claim as new and desire to secure by Letters Patent of the United States is:

1. In an implement for securing together a plurality of sheets, the combination of opposing members movable relative to one another with a straight line movement, cutting means carried by one of said members, a stripper for clearing cut paper from said cutting means, a substantially inelastic folder independent of said cutting means and pivotally mounted to swing with respect to said cutting means and arranged to push

the cut paper backward under the stripper, and a spring pressing against said pivotally mounted folder to hold it in position.

2. In a device for fastening sheets of paper, the combination of a cutting knife adapted to form a tongue from the paper, a slitting knife arranged to slit the paper near the base of the tongue, said slitting knife being provided with an eye near its cutting edge, a folder pivoted near said knives to swing toward said slitting knife, an arm projecting from said folder, and means for engagement with said arm to insure positive action of said folder in moving the tongue of paper into the eye of the slitting knife.

3. In a device for securing together sheets of paper, the combination of a cutting die, a knife coöperating therewith and adapted to form a tongue from the sheets of paper, a slitting knife arranged for slitting the paper near the base of the tongue, said knives being rigidly mounted with respect to one another, a folder pivoted between said knives, a spring normally urging said folder toward said slitting knife, and means brought into engagement with said folder near the end of the folding operation to insure positive operation of the folder in pressing the tongue backward through the eye in the slitting knife.

4. In an implement for securing together sheets of paper, the combination of two jaws mounted to move toward one another, operating handles for insuring parallel movement of said jaws, a tongue cutting knife and a slitting knife carried by one of said jaws, said slitting knife having an eye for the reception of a tongue of paper, a stripper plate yieldingly mounted between said jaws and having a projecting shoulder, and a folder pivotally mounted to move with one of said jaws and having an arm initially contacting with the shoulder on said stripper plate, said folder having a second arm arranged for contact with said shoulder when the jaws are at the limit of their movement toward one another, the stop on said stripper plate serving to insure positive ac-

tion of said folder in bending the paper 50 tongue backward through the eye of the slitting knife and for holding said tongue in such position that when said jaws move apart, the end of the tongue will be drawn through the opening previously made by 55 the slitting knife.

5. In a paper fastener of the type described and in combination, a punch, a needle having an opening, a tucker operating part and a pivotally mounted tucker 60 having a portion below its pivot coöperating directly with the tongues cut by the punch and having a portion above its pivot normally arranged in the path of said tucker operating part and designed to coact with 65 the latter for moving the part of the tucker below the pivot toward the opening of the needle, substantially as and for the purpose specified.

6. In a tool such as described, the combination of two jaws movable toward and away from each other, a tongue-cutting punch and a die on the respective jaws, a slit cutter on one of the jaws having an eye, a movable tongue inserter on one of the 75 jaws, having two arms, and means on the other jaw to engage one of said arms when the jaws are approached toward each other to a predetermined extent and thereby move the other arm toward the slit cutter eye. 80

7. In a tool such as described, the combination of a pair of jaws movable toward and away from each other, a tongue-cutting punch and a die on the respective jaws, a needle on the jaw carrying the punch, a 85 tongue inserter on the same jaw comprising a member pivoted intermediate of its ends, and a projection on the other jaw adapted to engage one end of said tongue inserter and thereby swing the other end toward 90 said needle.

In witness whereof, I hereunto subscribe my name.

J. C. HAWKINS.
